UNITED STATES PATENT OFFICE.

RUDOLPH A. BOEHM, OF ERIE, PENNSYLVANIA, ASSIGNEE TO RICKERT-SHAFFER COMPANY, OF ERIE, PENNSYLVANIA, A CORPORATION OF PENNSYLVANIA.

COLLAPSIBLE TAP.

1,345,744.

Specification of Letters Patent.

Patented July 6, 1920.

Application filed June 9, 1919. Serial No. 302,786.

To all whom it may concern:

Be it known that I, RUDOLPH A. BOEHM, a citizen of the United States, residing at Erie, in the county of Erie and State of Pennsylvania, have invented certain new and useful Improvements in Collapsible Taps; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to improvements in taps; particularly to that class thereof known as collapsible taps; the object of the invention being to provide a tap which is adjustable to thread work of varying diameters in which the cutters or chasers will be automatically released from contact with threads of the work after the tap has cut its required length, so that the tap can be removed from the work without the necessity of reversing or backing out of the threaded piece.

A further object of my invention is the provision of a tap of the character specified, which may be used for tapping to a depth greater than to the length of the chasers.

A further object of my invention is to provide a tap of the character specified, which may be used for right or left hand threading by changing the chasers only.

The features of my invention are herein-after fully described, explained, pointed out, and are illustrated in the accompanying drawings in which:

Figure 1, is a side elevation of my improved collapsible tap.

Fig. 2, is a vertical central section on the line 2—2 in Fig. 1, showing portions of the mechanism in elevation.

Fig. 3, is a plan view of the lower end thereof.

Fig. 4, is a central section of the body member thereof on the line 2—2 in Fig. 1.

Fig. 5, is a transverse section on the line 5—5 in Fig. 2.

Fig. 6, is an elevation of the lower end of the body member.

Fig. 7, is an elevation of the chaser operating member.

Fig. 8, is a view of the lower end thereof.

Fig. 9, is a side elevation of the operating cam.

Fig. 10, is a side elevation of the cam sleeve.

Fig. 11, is a longitudinal central section of the part of the operating mechanism shown in Fig. 7.

Fig. 12, is a side elevation of the micrometer adjusting ring.

Fig. 13, is a view of the upper edge of one of the chasers.

Fig. 14, is a side elevation of the shank hub with portions thereof broken away.

I am aware there are many collapsible taps shown and described in prior Letters Patent, but in all of those forms with which I am familiar there are many disadvantages which it is the object of the present invention to overcome.

In many of the other forms of taps the depth that can be tapped is limited by the length of the chaser plate for the reason that the operating mechanism of the tap is of greater diameter than that of the chasers.

In my improved tap A indicates the body member thereof, in the lower end of which are milled radial slots A' (see Fig. 6) which I preferably face with extra hard plates a and a' which are secured within the slots A' of the body member A by means of screws a² so that the faces of the radial slots A' will not become worn or abraded from use. This body A is cylindrical in contour, of uniform diameter throughout its entire length, and is provided with a cylindrical chamber A² which extends partially therethrough, and is provided at the intermediate portion thereof with internal threads A³.

At the inner end of the chamber A² is a central opening A⁴ of reduced diameter; the wall of said opening A⁴ being provided with longitudinal grooves a³, which grooves coincide with the central lines of the radial slots A'. A⁵ indicates a slot in the wall of the member A for the operating lever herein-after described. A⁶ indicates a sight opening in the wall of the body member A for the purpose herein-after described. a⁴

indicates a screw hole in the wall of the body member A for the purpose herein-after described. a⁵ indicates short longitudinal semi-cylindrical grooves in the interior surface of the body member A at the upper end

thereof. a^6 indicates screw holes in the lower end of the body member A.

Within the body member A I place a member B (see Figs. 7 and 8) having on the lower end thereof inclined radial ribs B' which are under cut on each side thereof; which ribs B' enter the slots C in the inner end of the chasers C' (see Fig. 13); the ribs B' passing downwardly through the grooves a^3 (see Figs. 4 and 6) in the reduced opening A⁴, so that when the chasers C' are placed within the slots A' in the lower end of the body A, the dove-tail like slots C in the inner ends of said chasers will embrace the ribs B' on the lower end of the member B so that a longitudinal movement of the member B will cause a radial movement of the chasers C'.

The member B is provided with cams B², which cams form a hub on the member B which fits into the reduced opening A⁴ of the body member A. The member B is provided with a longitudinal opening B³ in which I place a spring B⁴, which operates to maintain the member B in constant contact with the adjusting ring G. Secured upon the lower end of the body member A by means of screws H is a disk H' which retains the chasers C' within the slots A'. The disk H' is provided with the axle post H² which enters the longitudinal opening B³ in the member B, and compresses the spring B⁴ therein. The disk H' fits into a recess H³ (see Fig. 4) in the lower end of the body member A.

Upon the member B I place a circular operating member D which is of substantially the same diameter as the interior diameter of the body member A, and is provided with a circumferential groove D' (see Fig. 9) adapted to receive a coiled spring E (see Fig. 2) for the purpose hereinafter set forth. At the lower side of the operating member D are cams d adapted to coöperate with the cams B² on the member B to force the member B downwardly when the operating member D is turned toward the left. On the upper side of the operating member D are similar cams d' oppositely inclined.

Upon the member B above the operating member D (see Fig. 2) I non-rotatably secure a cam sleeve F (see Fig. 10) having cams F' on the lower end thereof adapted to coöperate with cams d' on the member D, as shown in Fig. 2; the cam sleeve F being secured on the member B by means of a transverse pin F², which passes through a transverse opening b in the upper end of the member B (see Fig. 11), so that when the operating member D is rotated toward the right the cams d' thereon will coöperate with the cams F' on the sleeve F to raise the member B upwardly and thus cause an inwardly radial movement of the chasers C' in the slots A'. The lower side of the operat-

ing member rests upon the surface A⁷ at the upper end of the reduced opening A⁴ (see Fig. 2), and within the body member A, I place an adjusting ring G (see Fig. 12) which is provided with screw threads G' which engage the screw threads A⁸ in the body member A, the lower edge of said ring G contacting with the upper surface of the operating member D, thereby preventing the operating member D from moving longitudinally within the body member A. The adjusting ring G is also provided with a knurled surface G² adapted to be engaged by the screw G³ (see Fig. 2) in the wall of the body member A, whereby said adjusting ring G may be secured against rotation within the body member A. Said adjusting ring G is also provided with a graduated scale G⁴, and with small holes G⁵ which are visible and accessible through the opening A⁶ in the wall of the body member A.

Secured to the operating member D within the groove D' by means of a screw D² is the coiled spring E; said spring E passing around back of the operating member D and being secured to the screw E' (see Fig. 2) in the wall of the body member A; said spring E being adapted to cause the operating member D to revolve toward the right. J indicates the operating lever which passes through the slot A⁵ and is secured in the opening d² (see Fig. 9) in the periphery of the operating member D, by means of which lever J the operating member D can be turned to the left to force the member B downwardly.

In the upper end of the body A I place the hub K of the shank K'. This hub K is provided in its periphery with semi-cylindrical grooves k (see Figs. 5 and 14) which coincide with the grooves a⁶ in the inner wall of the body member A. The grooves k in the hub K do not extend entirely across the width of the hub K, but stop short of the lower edge thereof thus leaving a ledge k' at the lower end of the grooves upon which the springs L rest. In others of the grooves k—a⁵ I place short rods M (see Figs. 2 and 5) which rods M prevent the hub K from rotating within the body member A.

Upon the upper end of the body member A I secure a ring N by means of screws N' which maintain the springs L and key-rods M in place and prevents the withdrawal of the hub K from the body member A. The inner end of the hub K is reduced in diameter, as at K² to permit it to enter into the adjusting ring G as shown in Fig. 2, and is provided with a central longitudinal opening K³ adapted to receive the cam-sleeve F. In the lower edge of the portion K² of the hub K there is a recess O in which I place a locking bolt P (see Fig. 2) which is secured therein by means of a bushing P'; said bolt P being normally held in extended position 130

as shown in Fig. 2 by means of a spring P^2 , in which position it extends into a hole in the operating member D as shown in dotted lines in Fig. 2, when the lever J is turned to 5 the position thereof shown in Fig. 2, to expand the chasers C'; said bolt P being withdrawn from said hole in the member D when the body member is moved longitudinally downward on the hub K thereby releasing 10 the member D and permitting it to be rotated in the body member A by the spring E so that the operating lever J will swing to the right, as shown in Fig. 1, and withdraw the chasers C' from the work, thus permitting 15 the tap to withdraw from the work without the necessity of reversing the tap.

In operation the shank K' of the tap is placed in the tool stock of the lathe, and the piece of work is revolved. The lever 20 J of the tap is manually swung to the position thereof shown in Fig. 2, so that the bolt P will lock the member D as shown in said figure, thus expanding the chasers C' through the forcing of the member B downward by the coöperation of the cams B^2 and 25 d and the inclined ribs B'.

When the tap has reached the limit of its 30 cut the tool stock and chaser are moved backward thus causing the body A to move longitudinally on the hub K and compress the springs L, and withdrawing the locking bolt P from its engagement with the member D, which, as above stated permits the spring E to rotate the member D to the 35 right; and because of the coöperation of the cams d' and F, which causes an upward movement of the member B, thus causing the chasers C' to withdraw from the work. To adjust the cutting diameter of the 40 chasers C' the ring G is turned to the right or left, as may be desired, thus permitting the members B and D to be raised or lowered, the scale shown on said ring in Fig. 12 being in substantially thousandths of an 45 inch.

Having thus fully shown and described the construction of the mechanism embodying my invention, and the operation thereof, I do not desire to be limited to the exact 50 form and arrangement thereof, as many modifications thereof will suggest themselves to those skilled in the art without departing from the scope of my invention; therefore, what I claim as new and desire to 55 secure by Letters Patent is:—

1. A collapsible tap comprising a body member having radial slots in one end thereof and a cylindrical chamber in the opposite end thereof, chasers slidably secured in 60 said slots, longitudinally movable means within said body member engaging the inner ends of said chasers adapted to shift the same, the diameter of said chasers being greater than the diameter of said body member, rotating means mounted on said longi- 65

tudinally movable means adapted to impart longitudinal movement thereto, a shank, a hub thereon slidably mounted within the cylindrical chamber in said body member, means to prevent rotary movement of said hub within said body member, and means to yieldingly press said hub inwardly in 70 said body member, substantially as set forth.

2. A collapsible tap comprising a body member of uniform diameter throughout its 75 length, and having radial slots in one end thereof, chasers slidably mounted in said slots the diameter of which is greater than the diameter of said body member, mechanism within said body member to shift said 80 chasers from expanded to collapsed position, a shank, a hub thereon slidably mounted within said body member, means to prevent said hub from rotating within said body member, means to yieldingly press said 85 hub inwardly with relation to said body member, means carried by said hub to lock the chaser shifting mechanism when the chasers are expanded when said hub is in its inward position, and to release it when 90 the body member is moved longitudinally on said hub, substantially as set forth.

3. A collapsible tap comprising a body member of uniform diameter throughout its 95 length, having radial slots in one end thereof, chasers slidably secured in said slots, longitudinally movable means within said body member to expand and collapse said chasers, a rotating operating member mounted on said longitudinally movable 100 means adapted to give longitudinal movement to the latter, means to yieldingly maintain said operating member in position to collapse said chasers, a non-rotatable longitudinally slideable shank secured in said 105 body member, means operated by said shank to lock the chaser expanding mechanism in expanded position and to unlock the same by means of relative longitudinal movement between the shank and body member, substantially as set forth.

4. A collapsible tap comprising a body member, one or more chasers radially mounted in one end of said body member, a longitudinally movable member in said body 115 member having one or more axially inclined beads engaging the inner end of said chaser adapted to transform the longitudinal movement of said member into the radial movement of said chaser, cams on said longitudinally movable member, a rotary operating member mounted on said longitudinally movable member, cams thereon adapted to coöperate with the cams on said longitudinally movable member to raise the same 120 upward or force the same downward, a spring to rotate said operating member in one direction, a lever to rotate the same in the opposite direction, means within said body member to secure said operating mem- 125 ber, rotating means mounted on said longi- 130

ber against longitudinal movement with relation to said body member, a spring pressed shank hub slidably and non-rotatably secured in said body member, a spring-pressed locking bolt carried by said shank hub adapted to engage said rotary operating member when it is operated by said lever, and to release the same when the body member is moved longitudinally on said shank hub, substantially as set forth.

5. A collapsible tap comprising a body member having radial slots in one end thereof and a longitudinal central opening therein communicating with said slots, a longitudinally movable member within said central opening, axially inclined beads therein extending radially into said radial slots, said member having a central longitudinal opening therein, a spring in said opening, chasers in said radial slots and engaging said inclined beads, a disk secured on said body member adapted to retain said chasers in said slots and incidentally to compress said spring, cams on said longitudinally movable member, an operating disk rotatably mounted on said longitudinally movable member, cams thereon to coöperate with the cams on said longitudinally movable member to raise and lower the same, an adjusting ring engaging threads within said body member adapted to resist the upward thrust of said operating disk due to the action of said spring, a non-rotatable and longitudinally movable spring-pressed shank hub within said body member, means to secure said hub within said body member, a spring-pressed locking bolt carried by said hub, a lever to rotate said disk until the same is engaged by said spring-pressed locking-bolt, and a spring to rotate said disk in the opposite direction to collapse said chasers when the locking bolt is disengaged from said disk by causing the outward movement of said hub body within said body member, substantially as set forth.

6. A collapsible tap comprising a body member, one or more chasers carried thereby, mechanism centrally mounted within said body member adapted to engage and shift the radial position of the chasers, means to adjust the longitudinal position of said mechanism within said body member spring mechanism to operate said mechanism to collapse said chasers, a shank slidably and non-rotatably secured within said body member, means carried by said shank to engage said centrally mounted mechanism and lock the same when the chasers are radially expanded, and release the same when the body member is moved longitudinally on said shank, substantially as set forth.

7. A collapsible tap comprising a body member, one or more radially shiftable

chasers carried thereby, a shank slidably and non-rotatably secured in the opposite end of said body member, a spring-pressed locking bolt secured in said shank parallel to the axis thereof, a longitudinally movable member centrally mounted within said body member, axially inclined beads on the lower end thereof adapted to engage chasers carried by said body member, whereby the longitudinal movement of said member is converted into the radial movement of said chasers, cams on said longitudinally movable member, a rotating disk mounted thereon, cams on said disk adapted to coöperate with the cams on said member to force the same upward or downward, an adjusting ring engaging screw threads within said body member to limit the upward movement of said disk, a spring to normally press said mechanism upwardly against said adjusting ring, a lever to turn said disk in one direction to be engaged by said locking bolt, and a spring to turn said disk in the opposite direction when released from said locking bolt, substantially as described.

8. A collapsible tap comprising a shank and a body member non-rotatably and slidably mounted thereon, springs to force said shank upwardly with relation to said body member, means to limit the axial movement of said members with relation to each other, radially slidable chasers mounted in the opposite end of said body member, a lever and spring operated rotary member longitudinally positioned within said body member, and a longitudinally adjustable ring secured within said body member above said rotary member, and mechanism centrally mounted in said body member and said rotary member adapted to convert the rotary movement into longitudinal movement, and then into radial movement of said chasers, means on said shank to maintain the rotary member in its lever-operated position, and to release it to the action of its operating spring when said body member is moved longitudinally on said shank, substantially as set forth.

9. A collapsible tap comprising a body member having a concentric chamber therein, and radial slots in the end thereof communicating with said chamber through a central opening of reduced diameter, shiftable chasers in said slots, mechanism mounted in said central opening adapted to engage and shift said chasers, rotatable means within said body member adapted to operate said mechanism, a spring to rotate the same in one direction, a lever projecting through a slot in the wall of said body member to manually rotate said means in the opposite direction, an adjusting ring engaging said internal screw threads in said body member to limit the upward move-

ment of said rotatable means, a shank non-rotatably and slidably secured in said body member having a portion thereof projecting into said adjusting ring, and having a recess in the end thereof parallel with the axis thereof, a spring pressed bolt in said recess adapted to lock said rotatable means at the limit of the manual operation thereof, and to release the same when said shank and body members have relative longitudinal movement, substantially as set forth.

10. In a collapsible tap, a body member having radially shiftable chasers mounted therein, longitudinally movable chaser-shifting mechanism, rotatable mechanism

within said body member adapted to control said chaser-shifting mechanism, a longitudinally movable shank non-rotatably secured within said body member, means to yieldingly maintain the shank in its innermost position within said body member, a spring pressed bolt carried by said shank adapted to engage said rotatable mechanism and maintain it in position to expand said chasers during the thread cutting operation, and to release the same when the tap is moved backward from the work, substantially as set forth.

In testimony whereof I affix my signature.
RUDOLPH A. BOEHM.
